UNITED STATES PATENT OFFICE

JOHN A. CASSELL, OF ADRIAN, MICHIGAN, ASSIGNOR TO THE SUNTERBACH COMPANY,
OF ADRIAN, MICHIGAN, A CORPORATION OF MICHIGAN

ARTICLE CASE

Application filed June 15, 1931. Serial No. 544,385.

This invention relates to small article holding cases of the type customarily made of leather and having narrow sides with an open end or side, and particularly to cigarette and 5 cigar cases, card cases, instrument, camera and medicine cases and portfolios.

The object of the invention is the provision of an article case of this character, which is composed of a minimum of material, is easily made, with little stitching, and has its side 10 walls reinforced both to strengthen the case and to facilitate the sliding of articles therein or removal of the same therefrom.

The invention is fully described in the following specification, and while in its broader aspect it is capable of embodiment in various forms, one embodiment thereof illustrated in the accompanying drawing, in which—

Figure 1 is a plan of the body blank from 20 which the case is made with the reinforcing member for the bottom and side walls attached thereto. Fig. 2 is a cigarette case embodying the invention with a portion of the reinforcing member broken away, and 25 Fig. 3 is a fragmentary section on the line 3—3 in Fig. 2.

A case embodying the invention is composed of two pieces of material, one constituting the body blank 1, and the other the reinforcing strip 2. The blank 1 is composed of the front and rear panel portions 3 and 4, which are joined together at their adjacent edges by a bottom edge panel 5 corresponding in length to the width of the panels 3 and 35 4. Attached to the outer edge of the rear panel 4, preferably integral therewith, is a flap 6 adapted to extend over and to close the upper open end of the case when the blank 4 is folded up to form a case. Each side edge 40 of the panels 3 and 4 is formed with extensions or side wings 7, which are coextensive in length with the lengths of said panels and in width are substantially the thickness of the case from front to rear, thus adapting 45 the extensions 7 at the same edges of the front and rear panels 3 and 4 to have edge-abutment with each other when the panels are folded upward in parallel relation, and the extensions are turned inward at right angles thereto. In other words, when the panels are

folded in parallel relation and the edge extensions 7 thereof are turned inward, such edge extensions cooperate to form the narrow sides of the case, which sides correspond in width to the width of the bottom panel 5. 55

The reinforcing strip 2 is secured in any suitable manner, preferably by sewing, centrally of its ends to the outer or bottom side of the bottom panel 5 lengthwise thereof, and when the front and back panels 3 and 4 and 60 the side extensions 7 thereof have been folded in case-forming relation, the end portions of the strip 2, which project beyond the ends of the bottom panel 5, are folded up along the respective sides of the case formed by the extension 7 and firmly secured thereto, preferably by gluing, so as to maintain the adjoining extension 7 in edgewise abutting relation. The ends of the strips are then turned into the 65 interior of the case and glued to the inner 70 surfaces of the side walls, being preferably of a length to extend to the lower ends of such sides.

It is apparent that the strip 2 not only serves to strengthen, stiffen and reinforce the 75 bottom panel 5, but also to join the adjacent extensions 7 together and to provide a double reinforcement and stiffening means for the sides of the case, as is apparent by reference to Fig. 3. The extension of the end portions 80 of the strip 2 down into the case at the sides thereof renders the inner surfaces of the sides smooth to facilitate the insertion of articles into and removal thereof from the case. 85

When the case has been formed up the extension 6 on the outer upper edge of the rear panel 4, provides a closure flap for the open end of the case, and is sufficient in length to extend over the top open end of the case 90 and a distance down the front side thereof, to which latter it is detachably secured in any suitable manner. In the present instance, the free end of the flap 6 is inserted between a strap 8 and the front side of the case, said 95 strap extending across the front side of the case and having its ends secured to the adjacent edge extensions 7 by stitching, or in any other suitable manner, as shown in Fig. 1. The stitched ends of the strap 8 are disposed 100

between the case sides and the strip 2 so that such ends are not exposed.

It is apparent that if the strap 8 is disregarded, the case is composed of only two pieces, namely, the body blank 1 and the reinforcing strip 2, and that after the forming of the body blank, the strip 2 is secured to the bottom 5 and to the sides formed by the adjoining extensions 7 in a simple and inexpensive manner, as, for instance, by stitching the strip midway of its ends to the bottom 5 and then cementing or gluing the same to the outer and inner surfaces of the case sides. The employment of the strip 2 to connect and reinforce the bottom and sides of the case, not only gives a finished and pleasing appearance, but materially strengthens the case against collapsing.

I wish it understood that my invention is not limited to any specific constructions, arrangement or form of the parts, as it is capable of numerous modifications and changes without departing from the spirit of the claims.

Having thus described my invention, what I claim as new and desire to secure by United States Letters Patent is:

1. A case of the class described, having connected front, back and bottom panels, the front and back panels having extensions at their side edges cooperating to form the case sides with the adjacent extensions in substantially edge-abutment, a reinforcing strip attached to the outer surface of the bottom panel and extending lengthwise thereof with its ends projecting up along the respective sides of the case and thence down into the case substantially to the bottom thereof and secured inside and out to said sides to unite and stiffen the extensions forming the same.

2. A case of the class described, having connected front, back and bottom panels, the front and back panels having extensions at their side edges cooperating to form the case sides with the adjacent extensions in substantially edge abutment, a reinforcing strip attached to the outer surface of the bottom panel and extending lengthwise thereof with its ends projecting up along the respective sides of the case and thence down into the case substantially to the bottom thereof and secured to said sides to unite and stiffen the extensions forming the same, and a closure flap extending from the outer edge of the rear panel and adapted to be extended over the open end of the case and detachably secured to the front panel thereof.

3. A case of the class described, having connected front, back and bottom panels, the front and back panels having extensions at their side edges cooperating to form the case sides with the adjacent extensions in substantially edge abutment, a reinforcing strip attached to the outer surface of the bottom panel and extending lengthwise thereof with

its ends projecting up along the respective sides of the case and thence down into the case substantially to the bottom thereof and secured to said sides to unite and stiffen the extensions forming the same, a strap extending across the front panel and having its ends lapping the side edge extensions of said panel and secured thereto between said reinforcing strip and such extension, and a closure flap extending from the outer edge of the rear panel and adapted to be extended over the open end of the case and inserted between the front panel and said strap.

In testimony whereof I have hereunto signed my name to this specification.

JOHN A. CASSELL.
